UNITED STATES PATENT OFFICE.

JOHN EDGAR HOWARD, OF DAVENPORT, WASHINGTON.

FOLDING BED FOR AUTOMOBILES.

1,268,717.

Specification of Letters Patent. Patented June 4, 1918.

Application filed October 31, 1917. Serial No. 199,533.

To all whom it may concern:

Be it known that I, JOHN EDGAR HOWARD, a citizen of the United States, residing at Davenport, in the county of Lincoln and State of Washington, have invented certain new and useful Improvements in Folding Beds for Automobiles, of which the following is a specification.

My invention relates to folding beds for automobiles, and is specially adapted for quickly providing a temporary bed in an automobile for the use of campers or other parties who, either from necessity or choice may find it desirable to sleep in the automobile.

My object is to provide a bed of this kind which can be easily and quickly placed in position for use in the automobile, and which can as easily be taken down and folded up into a short compact roll, so that it can be conveniently carried in the machine and will take up but little room.

Another object is to utilize the cushions of the automobile seats in forming the bed.

Other specific objects will appear in the subjoined description.

The invention consists in certain novel features of construction and arrangement of parts, as will be hereinafter described and claimed, reference being had to the accompanying drawings, in which;

Figure 1 is a perspective of an automobile showing my improvement in operative position therein, the side curtains being omitted for clearness.

Fig. 2 is a partial side view of the device, showing the method of holding the upper flexible portion spaced from the supporting slats beneath.

Fig. 3 is a top plan view of the bed, with portions broken away to more clearly disclose the construction.

Fig. 4 is a broken plan view—on a somewhat enlarged scale—of the slatted portion of my device as it appears when ready to be rolled up, and;

Fig. 5 is a view showing the slatted portion rolled up, with the canvas portion wrapped around it.

The numeral 1 indicates the flexible top portion of my improved bed, which may be formed of any suitable material, such as heavy sheeting, ticking, duck, canvas, etc. The forward end of this flexible portion 1 is folded backwardly upon itself a short distance and is secured in this position by a

row of stitching 2; and in the loop thus formed, the rod 3 is received. This rod is suitably held against longitudinal movement in its loop by means of the cords or wires 4 which pass through the two plies of flexible material just at the rear of the rod at 5, and are tightly secured around the same on the outside of the canvas, as shown in Fig. 3. The cords 6 are secured to the forward end of the flexible portion by means of the cords or bands 4. The rear end of the flexible portion is also provided with a loop 7 which carries the transverse rod 8 which is held in position in the loop by any suitable means, as for instance by the tacks 9. The rod 8 is provided near each end with an opening 10, as indicated in Figs. 2 and 3, and in order that these openings may be exposed, for a reason to be noted later, the loop 7 is provided with the elongated openings 11, (Fig. 3).

The under portion of my device consists of a series of parallel slats 12, preferably of a length slightly greater than one half the length of the flexible portion 1. These slats are held together in a well known manner by means of the tapes 13 by which the slats are woven together, so to speak, near their forward and rearward ends, the slats being provided with the elongated openings 14 through which the tapes 13 are passed to hold the slats against longitudinal movement relatively to each other.

The extreme outer slats 12^a of the lower or slatted portion of my device are provided with supports 15, which in appearance resemble strap hinges, having the lower portions 15^a (which are rigidly secured in any ordinary manner to the slats 12^a) and the upwardly extending free ends 15^b provided near their extremities with the openings 16 (Figs. 2 and 4).

Each slat 12^a is also provided with a brace rod 17 and a hook 18 which parts are pivotally secured to the slats by means of staples 19, the hooks 18 being connected with said staples by means of links 20.

The brace rod 17 is also provided near its free end with a rigid abutment 17^a.

When it is desired to place my device in operative position on an automobile, the bottom or slatted portion of my device is placed on the automobile seats, as indicated in Fig. 1, and the free ends 15^b of the supports 15 are moved upwardly and forwardly into the position indicated in Fig. 2 with the

outer ends of the brace rods 17 received into the openings 16 with the free ends 15^b of the supports in engagement with the abutments 17^a. The rear end of the flexible portion 1 of my device is then mounted on the supports 15 by passing the ends of the brace rods 17 through the openings 10 of the rod 8, which openings 10 are rendered accessible by means of the elongated openings 11 in the loop 7. The forward end of the flexible portion 1 is then secured to the frame of the wind shield of the automobile by means of the cords 6, which are drawn up sufficiently to render said flexible portion taut. 15 The hook 18 engaging the ring 21 at the rear end of the automobile will not permit the slatted portion of the device to move forwardly out of engagement with the top of the rear seat, when the flexible portion 20 is thus drawn forwardly. The cushions 22 are then removed from the seats of the automobile and placed on the slats 12 between said slats and the flexible portion 1 of the device, the height of the supports 15 being 25 approximately equal to the thickness of the cushions.

When it is desired to fold up the bed, the free ends 15^b of the supports 15 are folded forwardly and downwardly into engagement with their respective slats 12^a, and the brace rods 17 and the hooks 18 with their connecting links 20 are also folded forwardly into flat engagement with said slats 12^a, all as shown in Fig. 4; and then the slats are 30 rolled up into a roll, and the flexible portion 1 is wrapped around them and tied with the cords 6, as indicated in Fig. 6. The roll thus formed can be stowed away in the automobile, and will take up but little 35 room.

Having thus described my invention, what I claim as new and desire to secure by Letters Patent is:-

1. A device of the character described, 45 comprising a lower portion designed to be supported on the backs of the automobile seats, and formed of slats hinged together laterally to permit the slats to be rolled up into a roll when not in use; an upper portion formed of flexible material; a folding support interposed between said upper and lower portions, said support being hinged at its lower end to said lower portion with the hinge arranged to fold inward, and 50 adapted at its free upper end to detachably connect with said upper portion and arranged to rigidly hold the same sufficiently spaced from each other for the reception of the automobile cushions between them.

2. A device of the character described, 55 comprising a lower portion designed to be supported on the backs of the automobile seats, and formed of slats hinged together to permit the slats to be rolled up into a roll when not in use; an upper portion 60 formed of flexible material; folding supports interposed between said upper and lower portions and adapted to hold said parts spaced from each other, each support comprising a hinge having one of its wings 65 secured to said lower slatted portion and having its other wing free and adapted to swing upwardly therefrom; and a brace rod also pivoted to said slatted portion and adapted to swing upwardly therefrom, said 70 brace rod being adapted to engage and hold said free wing in its upward position; and means for engaging and holding said upper flexible portion on said support.

3. A device of the character described, 75 comprising a lower portion designed to be supported on the backs of the automobile seats, and formed of slats hinged together laterally to permit the slatted portion to be rolled up into a roll when not in use; an upper portion formed of flexible material; a transverse bar at the end of said flexible portion; folding supports interposed between said upper and lower portions and adapted to hold said parts spaced from each other, each support being hinged at its lower end to said lower slatted portion near the end of said portion, and having its upper end free and adapted to swing upwardly and also inwardly into parallelism with said 90 lower portion; and brace rods also pivoted at one end to said slatted portion at a point between said hinged supports and the longitudinal center of the slatted portion, said 95 brace rods having their free ends toward 100 said supports and being adapted when not in use to lie in flat engagement with said lower portion of the device, and, when desired for use, to swing upwardly therefrom at their free ends, the upper free ends of 105 said support having openings adapted to receive the free ends of said brace rods, said rods being provided with stops to limit the inward movement of said free ends of the supports on said rods, said stops being 110 spaced from the ends of said rods to permit said ends to project beyond the supports; and said transverse bar of the flexible portion of the device having openings adapted to receive the projecting ends of said rods. 115

In testimony whereof I affix my signature.

JOHN EDGAR HOWARD.
